(57) **CLAIM**

I claim the ornamental design for an inflatable swimming pool cover, as shown and described.

DESCRIPTION

FIG. 1 is a perspective view of the inflatable swimming pool cover embodying the design of the present invention.

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of environmental structure is for illustrative purposes only and forms no part of the claimed design.

1 Claim, 4 Drawing Sheets

FIG. 1.

FIG. 2.

FIG. 3.
